COOLING OF PISTONS

Harry Ralph Ricardo, London, England

Application August 27, 1943, Serial No. 500,280
In Great Britain July 20, 1942

10 Claims. (Cl. 123—176)

This invention relates to the cooling of pistons and particularly pistons of a known type in which the piston is made in two parts, namely an inner member which carries the gudgeon pin, and an outer part comprising the crown and skirt within which the inner member is secured by bolts passing through the crown. The object of the invention is to provide a construction in which a cooling of the crown and gas pressure rings can be effected by means of lubricating oil which is caused to be delivered through the connecting rod.

According to this invention radial grooves are provided in that face of a part forming a disc-like crown of the inner part of the piston which lies against the inner face of the crown of the outer part and these grooves lead into an annular space or chamber which is arranged within the outer part and between it and the periphery of the inner part so that oil which is caused to flow from the engine crankshaft through the connecting rod into these radial grooves will pass into this annular space and having effected the desired cooling can flow away between the exterior of the inner part and the inner surface of the outer part of the piston. The grooves in the face of the inner part or member radiate from a central opening into which open one or more passages in the small end of the connecting rod through which oil can issue which has been caused to flow through a longitudinal passage in the connecting rod. The annular space between the inner and outer parts of the piston is so formed in the outer part that it extends behind all the external grooves which carry the gas pressure rings on the outer part in order that a cooling of these rings shall be effected. The outer part of the piston comprising the crown and the skirt is wholly turned and is symmetrical about the piston axis being circular and of uniform thickness circumferentially in any plane normal to the piston axis.

In order to prevent leakage and ensure that all the oil flowing through the connecting rod will pass from the small end of that rod into the central passage through the inner part of the piston, it is desirable to provide a spring-loaded telescopic tubular connection forming an oil collector between the passage through the crown of that part of the piston and the hole through which the oil issues from the small end of the connecting rod. This oil collector conveniently comprises a tubular plug inserted through the upper face of the crown of the inner part of the piston

and a tubular member which can slide telescopically either on or in the lower or outer end of the plug and is maintained by the action of a spring in contact with the surface of the adjacent end of the connecting rod. Such a spring-loaded oil collector is especially required in the case where the improved piston is used in an internal combustion engine operating on the four-stroke cycle.

10 The piston to which the invention is particularly applied is built up of two parts for convenience of manufacture, these two parts being secured together by bolts which are passed through the crown of the outer part and through 15 a disc-like part or crown of the inner member which lies against the inner side of the crown. The inner member is supported laterally by a rib which projects from the lugs which carry the gudgeon pin and lies within a corresponding inwardly projecting annular rib within the skirt portion of the outer part of the piston. There is such clearance between these engaging projections that oil can leak away between them after it has performed its cooling on the piston.

25 The accompanying drawings illustrate by way of example how the invention may be carried out in practice. In these drawings—

Figure 1 is a longitudinal sectional elevation of the complete piston, the section being taken in the plane which contains both the axis of the piston and also the axis of the gudgeon pin.

Figure 2 is a similar view, but the section is taken in a plane at right angles to the plane of the section in Figure 1 that is to say in a plane normal to the gudgeon pin axis.

Figure 3 is a sectional elevation of the inner part of the piston as seen in Figure 1, but shown by itself.

40 Figure 4 is a similar view of the inner part of the piston, but the section is taken in the same plane as the section shown in Figure 2.

Figure 5 is a plan of the inner part when removed.

45 Figure 6 is an under side view of the same part and as seen in Figure 4.

Figure 7 is a sectional elevation of the outer part of the piston as seen in Figure 1, but shown by itself.

50 Figure 8 is a side elevation of the inner part as first turned up and before cutting away portions of the skirt part to form the lugs for the gudgeon pin bearings.

Figure 9 is a sectional elevation of the complete piston and connecting rod the section being taken

on the line 9—9 in Figure 10, that is in a plane normal to the crankshaft axis and showing a somewhat modified formation of the inner part of the piston.

Figure 10 is a similar section taken on the line 10—10 in Figure 9.

Figure 11 is a side elevation of the crank pin showing the oil passage through its wall.

Figure 12 is a transverse section of the crank pin on the line 12—12 in Figure 11.

Figures 13 and 14 are longitudinal sectional elevations in planes at right angles, and similar to Figures 1 and 2, but showing a modified arrangement of the oil collector between the small end of the connecting rod and the crown of the inner part of the improved piston.

The outer part of the piston comprises the crown A, the flange A¹ in which are the grooves A² for the gas pressure rings, and the skirt A³. Within the skirt of this part of the piston is an annular rib A⁴ and between this rib and the crown A are two annular recesses B and B¹ of which the former is formed in the flange A¹ around a part A⁵ which is thus caused to project on the inner side of the crown and has a flat face. This recess B also lies behind the grooves A² and has between it and the rib A⁴ the other recess B¹ which is surrounded by a part of the skirt A³. The separate inner part of the piston in itself somewhat resembles a piston having a disc forming a crown C with a flat face which lies in contact with the flat face of the part A⁵ and in which are a series of grooves C¹ radiating from a central opening C². When this inner part is in place in the outer part the periphery C³ of the crown C of the inner part lies just clear of the inner surface of the flange A¹ of the outer part so as to leave an annular gap D which serves as a communication between the inner annular recess B and the other annular recess B¹ as can be clearly seen in Figures 1 and 2. The crown C has a skirt-like part C⁴ having on its exterior an annular rib C⁵ of which portions are cut away as at C⁶, see Figure 6. The projecting parts of this rib C⁵ lie in contact with the inner face of the annular rib A⁴ within the skirt of the outer part of the piston when the whole is assembled thus giving lateral support for the inner part. A recess B² in the skirt C⁴ between the periphery C³ of the crown C and the rib C⁵ cooperates with the recess B¹ within the outer part of the piston to form an annular chamber with which as mentioned the recess B is in communication through the gap D. Thus oil passing up through the opening C² can travel by way of the radial grooves C¹ into the annular chamber constituted by the recess B and thence through the gap D constituting a constriction into the annular chamber B¹ B², and from there it can pass through the spaces C⁶ in the rib C⁵ into the outer part of the skirt A³.

The inner part C has lugs E projecting or formed from the skirt C⁴ and in these lugs are bearings E¹ for the gudgeon pin F. Bolts G extending from the crown A of the outer part run through these lugs and serve to rigidly connect together the two parts of the piston.

On its under side the part of the crown C of the inner part around the central opening C² is formed as at C⁷ with a seating to engage the outer surface of the small end of the connecting rod H. According to the external finish of the latter this seat may be cylindrical or spherical, but preferably it is cylindrical as shown in the drawings. The oil which is caused to come up in the passage H¹ which runs through the con-

necting rod H flows round in a groove H² within the small end to an outlet opening H³ and thence by way of the central opening C² and radial grooves C¹ in the crown C of the inner part to effect a cooling of the crown A of the outer part, the rings in the grooves D and the skirt A³.

In the modified construction shown in Figures 9 and 10, the seating for the small end of the connecting rod about the central opening in the crown C of the inner part of the piston is constituted by an inserted tubular plug J the upper end of which is flanged at J¹ externally and the flange seats in a recess around the opening in the face of the crown C. The inner end of the tubular plug J, which serves as an oil collector, lies in contact with the surface of the small end of the connecting rod. In the flanged end J¹ radial notches or grooves J² are formed to register with the ends of the radial grooves C¹ in the flat face of the crown C so that the oil coming up through the opening H³ in the end of the connecting rod H can pass through the bore J³ in the member J and by way of the grooves C¹ into the annular chambers B and B¹.

25 The oil flow from the crankshaft up through the connecting rod H is ensured in some known manner such as is commonly designated a timed delivery in that the delivery can take place only while the crank pin is moving between determined angular positions so arranged that oil can enter the connecting rod only while the inertia forces on the oil are acting in a direction towards the piston. Alternatively, a non-return valve may be arranged in the passage H¹ through 30 the connecting rod, this valve for example being in the form of a disc which is disposed in a recess in the end of the passage H¹ near the big-end, the seating of the valve being in a removable plug. A convenient arrangement, however, to effect a 35 timed delivery is shown in Figures 9, 10, 11 and 12. Oil is forced in the usual manner through the hollow crankshaft K into the interior of the crank pin L which has a radial hole L¹ through its wall opening into a groove L² which runs for 40 a short distance circumferentially in the surface of the crank pin. The hole L¹ runs at right angles to a line joining the axes of the crank pin and the crankshaft. In the bearing shell M there are holes M¹ opening into a groove N which extends in the circumferential direction within the big-end H⁴ for a determined distance and terminates in the end of the passage H¹. The direction of rotation of the crankshaft is indicated by the arrow O in Figure 9. It will be seen that oil 45 can only flow from within the crank pin L into the passage H¹ while the hole L¹ is passing through an angular position in which this hole registers, through the holes M¹ in the bearing shell, with the circumferential groove N. The 50 left hand crank pin shown in Figure 9 is just approaching the angular position in which oil can begin to flow to the passage H¹, while the right hand crank pin is in a position wherein the hole L¹ is nearing the end of the groove N, when the 55 oil flow will be cut off.

By this means oil is caused to flow intermittently up through the connecting rod and into the annular chambers or spaces B B¹, and the space B is kept at least partially filled with oil 60 by reason of the resistance to the free flowing away of the oil caused by the narrow annular gap D. This gap is arranged in a place which lies behind the lowest of the grooves A² or as shown in the drawings in a plane normal to the piston axis which lies below but near this lowest groove.

By keeping the annular space or chamber B partially filled with oil this oil is shaken about thereby by the movement of the piston and thus caused to come into intimate contact with the metal forming the walls of this space. From the chamber B¹ the oil is discharged downwardly past the annular rib A⁴, the latter defining a second annular gap which retards discharge of oil from chamber B¹.

From two of the radial grooves C¹ holes P run into the gudgeon pin bearings in the lugs E.

In the modified construction shown in Figures 13 and 14 there is provided a spring-actuated oil collector between the inner part C of the piston and the small end of the connecting rod H, an arrangement which is particularly desirable where the improved piston is employed in an engine operating on the four-stroke cycle so as to obviate leakage of oil at this place. In this construction the tubular plug J⁴ has an external diameter appreciably less than the internal diameter of the central hole C⁶ in the crown C of the inner part of the piston. The plug is centered in this hole by the flange J⁵ at its upper or inner end which lies in and engages an annular recess formed in the face of the crown. This end of the plug has radial notches to register with the ends of the radial grooves C¹ in the face of the crown. On the main cylindrical part J⁴ of the plug fits and can slide telescopically a tubular member Q which thus lies in the annular space in the hole C⁶ around the plug J⁴. At its outer end this sliding member Q has an external flange Q¹ which also extends partially internally where there is a diametrical slot Q² adapted to register with the hole H³ through which the oil issues from the small end of the connecting rod. The end face of the sliding member Q is curved to lie in contact with the cylindrical surface of the end of the connecting rod. These parts are maintained in contact by the action of a coiled spring R which surrounds the sliding member Q and lies between its end flange Q¹ and the adjacent face of the crown C of the piston part. This arrangement avoids the tendency for the collector to be lifted out of contact with the end of the connecting rod as may occur in a four-stroke engine at the end of the exhaust stroke when no substantial gas pressure exists in the engine cylinder. If found desirable the tubular member Q may be arranged to slide within the plug J⁴.

Where the inner part of the piston is made from a metal such as an aluminium alloy having a high coefficient of expansion, the bolts G by which the two parts of the piston are connected together are preferably made from a ferrous alloy which also has a high coefficient of expansion.

The improved construction of piston has certain advantages arising in the first place from the form of the outer part. Since this is completely symmetrical, circular and of uniform thickness in any plane normal to its axis, this part may be produced by turning. Secondly, owing to this symmetrical formation the risk of distortion due to heat effects is avoided. Thirdly by reason of the two-part construction there is an absence of stress transmission through the outer member as might result from gas loads on the crown of the piston.

What I claim as my invention and desire to secure by Letters Patent is:

1. A piston comprising in combination an outer part constituted by a crown the underside of which is flat and a skirt formed integral with the

crown and symmetrical about the piston axis by turning and having uniform thickness radially in any plane normal to the piston axis, at least one circumferential groove in the exterior of the skirt of this outer part this groove being adapted to contain a piston ring, an inner member comprising a crown, a skirt and within the latter lugs in which are bearings for the gudgeon pin, grooves radiating from a central opening in the otherwise flat face of the crown of the inner member, means by which the inner member is connected to the said outer part with the grooved face of the crown of the inner member in contact with the flat inner face of the crown of the outer part, an annular chamber within the said outer part located where at least a part of this chamber lies behind the said piston ring grooves, this chamber lying between the outer part and the periphery of the said inner member into which chamber lead the outer ends of the said radial grooves, and means by which oil flowing from the engine crankshaft through the connecting rod is caused to pass from the latter into and up the said radial grooves into the said annular chamber whence the oil passes away between the skirts of the outer part and of the inner member.

2. A piston comprising in combination an outer part constituted by a crown the underside of which is flat and a skirt formed integral with the crown and symmetrical about the piston axis by turning and having uniform thickness radially in any plane normal to the piston axis, an inner member comprising a crown, a skirt and within the latter lugs in which are bearings for the gudgeon pin, grooves radiating from a central opening in the otherwise flat face of the crown of the inner member, at least two annular parts spaced apart on the exterior of the inner member these parts being respectively adjacent to and at least in part lying in contact with the interior of the skirt of the said outer part, means by which the inner member is connected to the said outer part with the grooved face of the crown of the inner member in contact with the flat inner face of the crown of the outer part, an annular chamber within the said outer part and between it and the periphery of the said inner member into which chamber lead the outer ends of the said radial grooves, and means by which oil flowing from the engine crankshaft up the connecting rod is caused to pass from the latter into and through the said radial grooves into the said annular chamber whence the oil passes away between the skirts of the outer part and of the inner member.

3. A piston comprising in combination an outer part constituted by a crown the underside of which is flat and a skirt formed integral with the crown and symmetrical about the piston axis by turning and having uniform thickness radially in any plane normal to the piston axis, an inner member comprising a crown, a skirt and within the latter lugs in which are bearings for the gudgeon pin, grooves radiating from a central opening in the otherwise flat face of the crown of the inner member, bolts passing through the crown of the said outer part and through the said inner part and serving to connect the inner member to the outer part with the grooved face of the crown of the inner member in contact with the inner face of the crown of the outer part, an annular chamber within the said outer part and between it and the periphery of the said inner member into which chamber lead the outer

ends of the said radial grooves, and means by which oil flowing from the engine crankshaft up the connecting rod is caused to pass from the latter into and through the said radial grooves into the said annular chamber whence the oil passes away between the skirts of the outer part and of the inner member.

4. A piston comprising in combination an outer part constituted by a crown the underside of which is flat and a skirt formed integral with the crown and symmetrical about the piston axis by turning and having uniform thickness radially in any plane normal to the piston axis, an inner member comprising a crown, a skirt and within the latter lugs in which are bearings for the gudgeon pin, a central opening in the crown of this inner member, a bearing surface within this part about the said central opening against which surface lies the gudgeon pin end of the connecting rod, grooves in the otherwise flat face of the crown of the inner member, these grooves radiating from the said central opening in this crown, means by which the inner member is connected to the said outer part with the grooved face of the crown of the inner member in contact with the flat inner face of the crown of the outer part, an annular chamber within the said outer part and between it and the periphery of the said inner member into which chamber lead the outer ends of the said radial grooves, and means by which oil flowing from the engine crankshaft up the connecting rod is caused to pass from the latter and the said central opening in the crown of the said inner member into and through the said radial grooves into the said annular chamber whence the oil passes away between the skirts of the outer part and of the inner member.

5. A piston comprising in combination an outer part constituted by a crown the under side of which is flat and a skirt formed integral with the crown and symmetrical about the piston axis by turning and having uniform thickness radially in any plane normal to the piston axis, an inner member comprising a crown, a skirt, and within the latter lugs in which are bearings for the gudgeon pin, grooves radiating from a central opening in the otherwise flat face of the crown of the inner member, a peripheral part of the inner member which lies adjacent to but not in contact with an annular part of the interior of the skirt of the outer part and forming therewith an annular chamber within the said outer part and between it and the periphery of the said inner member into which chamber lead the outer ends of the said radial grooves, an interrupted annular rib on the exterior of the inner member which is spaced apart from said peripheral part of the crown of that member this rib being at least in part in contact with an annular rib within the skirt of the outer part and forming therewith a second annular chamber between the inner member and the outer part, and means by which oil flowing from the engine crankshaft up the connecting rod is caused to pass from the latter into and through the said radial grooves into the said first annular chamber whence the oil passes away through the said second annular chamber and between the skirts of the outer part and of the inner member.

6. A piston comprising in combination an outer part constituted by a crown the underside of which is flat and a skirt formed integral with the crown and symmetrical about the piston axis by turning and having uniform thickness radially in any plane normal to the piston axis, at least one

circumferential groove in the exterior of the skirt of this outer part this groove being adapted to contain a piston ring, an inner member comprising a crown, a skirt and within the latter lugs in

5 which are bearings for the gudgeon pin, grooves radiating from a central opening in the otherwise flat face of the crown of the inner member, at least two annular parts spaced apart on the exterior of the inner member these parts 10 being respectively adjacent to and at least one of them in part lying in contact with the interior of the skirt of the said outer part, means by which the inner member is connected to the said outer part with the grooved face of the crown of the inner member in contact with the flat inner face 15 of the crown of the outer part, an annular chamber within the said outer part located where at least a part of this chamber lies behind the said piston ring grooves this chamber lying between the outer part and the periphery of the said inner member into which chamber lead the outer ends 20 of the said radial grooves, and means by which oil flowing from the engine crankshaft up the connecting rod is caused to pass from the latter into and through the said radial grooves into the 25 said annular chamber whence the oil passes away between the skirts of the outer part and of the inner member.

7. A piston comprising in combination an outer part constituted by a crown the underside of which is flat and a skirt formed integral with the crown and symmetrical about the piston axis by turning and having uniform thickness radially in any plane normal to the piston axis, at least one circumferential groove in the exterior of the skirt of this outer part this groove being adapted to contain a piston ring, an inner member comprising a crown, a skirt and within the latter lugs in which are bearings for the gudgeon pin, a central opening in the crown of this inner member, a bearing surface within this part about the said central opening against which surface lies the gudgeon pin end of the connecting rod, grooves in the otherwise flat face of the crown of the inner member, these grooves radiating from the said central opening in this crown, means by which the inner member is connected to the said outer part with the grooved face of the crown of the inner member in contact with the flat inner face of the crown of the outer part, an annular chamber within the said outer part located where at least a part of this chamber lies behind the said piston ring grooves this chamber lying between the outer part and the periphery of the said inner member into which chamber lead the outer ends of the said radial grooves, and means by which oil flowing from the engine crankshaft up the connecting rod is caused to pass from the latter through the said bearing surface and the said central opening in the said inner member into and through the said radial grooves into the said annular chamber whence the oil passes away between the skirts of the outer part and of the inner member.

65 8. A piston comprising in combination an outer part constituted by a crown the underside of which is flat and a skirt formed integral with the crown and symmetrical about the piston axis by turning and having a uniform thickness radially in any plane normal to the piston axis, at least one circumferential groove in the exterior of the skirt of this outer part this groove being adapted to contain a piston ring, an inner member comprising a crown, a skirt and within the latter lugs in which are bearings for the gudgeon pin,

grooves radiating from a central opening in the otherwise flat face of the crown of the inner member, a peripheral part of the inner member which lies adjacent to but not in contact with an annular part of the interior of the skirt of the outer part and forming therewith an annular chamber within the said outer part located between it and the periphery of the said inner member where at least a part of this chamber lies behind the said piston ring grooves and with the outer ends of the said radial grooves leading into this chamber, an interrupted annular rib on the exterior of the inner member which is spaced apart from the said peripheral part of the crown of that member this rib being at least in part in contact with an annular rib within the skirt of the outer part and forming therewith a second annular chamber between the inner member and the outer part, and means by which oil flowing from the engine crankshaft up the connecting rod is caused to pass from the latter into and through the said radial grooves into the said first annular chamber whence the oil passes away through the said second annular chamber and between the skirts of the outer part and of the inner member.

9. A piston comprising in combination an outer part constituted by a crown the underside of which is flat and a skirt formed integral with the crown and symmetrical about the piston axis by turning and having a uniform thickness radially in any plane normal to the piston axis, an inner member comprising a crown, a skirt and within the latter lugs in which are bearings for the gudgeon pin, a central passage through the

5 crown of the inner member and grooves radiating from this opening in the otherwise flat face of this crown, means by which the inner member is connected to the said outer part with the grooved face of the crown of the inner member in contact with the flat inner face of the crown of the outer part, an annular chamber within the said outer part and between it and the periphery of the said inner member into which lead the outer 10 ends of the said radial grooves, a connecting rod to the small end of which oil flows up the rod from the engine crankshaft, and a yielding tubular connection constituting an oil collector between the small end of the connecting rod and the said central passage through the crown of the said inner member and serving to lead the oil without leakage from the connecting rod to the said radial grooves through which it flows to the said annular chamber whence it passes away between the skirts 15 of the said two piston parts.

10. A piston comprising in combination the parts as set out in claim 9 in which the said oil collector is constituted by a tubular plug inserted in the said central passage through the crown of the said inner piston member, a tubular member which can slide telescopically on the tubular plug with its outer end bearing on the surface of the small end of the connecting rod wherein is an opening through which issues the oil passing up the connecting rod, and a spring which maintains the end of the said tubular member in contact with the said surface of the small end of the connecting rod.

HARRY RALPH RICARDO.
